(57) **CLAIM**

The ornamental design of a connector, as shown and described.

DESCRIPTION

This design application is related to U.S. utility application Ser. No. 10/757,173 entitled “Connector Assembly” and to U.S. design application Ser. No. 29/197,415 also entitled “Connector”, to the same inventors, which are incorporated herein by reference, and having been filed concurrently with the present design application.

FIG. 1 is a perspective view of a connector according to the present invention;

FIG. 2 is a front view of the design shown in FIG. 1;

FIG. 3 is a rear view of the design shown in FIG. 1;

FIG. 4 is a left side view of the design shown in FIG. 1, the right side of which is a mirror image;

FIG. 5 is a top view of the design shown in FIG. 1; and,

FIG. 6 is a bottom view of the design shown in FIG. 1. The broken lines in the drawings are for illustrative purposes only and form no part of the claimed design.
